DRIVING MEANS FOR SHEET FEEDERS

Elmer W. Belluche and Frank R. Belluche,
Racine, Wis.

Application June 7, 1940, Serial No. 339,220

18 Claims.

(Cl. 271—37)

This invention relates to sheet feeders of the type used in conjunction with printing presses and similar machines and refers particularly to the manner of driving the feeders.

As is well known, the function of a sheet feeder is to separate the sheets from a source of supply and forward them singly to the press or other machine being fed, a suitable conveyor being provided to carry the sheets from the supply to the press or other machine.

There are two general types or classifications of sheet feeders, one known as the pile type, and the other, the continuous type; and while in each case the conveyor is apt to be quite long, it is particularly so in the newer forms of continuous feeders, such as illustrated in Reissue Patent No. 20,194, wherein the feeder is loaded at an elevation close to the floor and the sheets travel upwardly and forwardly a substantial distance before reaching the front guides of the press.

The drive for the feeder and conveyor, which is really part of the feeder, is taken from the press or other machine being fed to insure synchronism. This is usually done by means of a power take-off shaft driven from the press or other machine being fed, and having a clutch controlled driving connection with the main power input shaft of the feeder.

To permit turning the feeder over by hand during its adjustment for sheets of different sizes, the clutch is unidirectional or overrunning; and to insure synchronism between the feeder and press, the clutch has but a single driving position.

Heretofore, after the operator adjusted and properly loaded the feeder, he had the alternative of either driving the feeder from the press, in which case the press would run for quite a number of cycles without printing, as sheets would not pass through it until the entire conveyor was filled; or laboriously turning the feeder over by hand the required number of cycles to fill the conveyor and advance the first sheet to the front guides of the press.

The latter procedure is objectionable for obvious reasons, especially where the conveyor is quite long and the sheets are fed in under-lapped relation, which is known to the industry as stream feeding.

The former method is also objectionable, as it results in overinking of the form and the necessity of discarding quite a number of the first sheets to pass through the press.

It is, therefore, an object of this invention to provide a novel power drive for the feeder entirely independent of the press or other ma-

chine being fed, so that the feeder and conveyor may be power driven to advance the sheets until the leading sheet arrives at the front guides of the press or other machine being fed.

Another object of this invention is to provide means whereby the independent power drive for the feeder is automatically rendered inoperative upon the leading sheet arriving at the front guides of the press.

10 In this connection, it is also an object of this invention to provide means for adjusting the mechanism which renders the independent drive inoperative, to accommodate conveyors of different lengths.

15 Another object of this invention is to provide a novel clutch arrangement whereby upon initial operation of the independent power drive means, a driving connection is established between it and the main power input shaft of the feeder and whereby the independent power drive means becomes disconnected from the feeder during the initial application of driving force from the press or other machine.

With the above and other objects in view which 25 will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate two complete examples of the physical embodiment of the invention constructed in accordance with the best modes so far devised for the practical application of the principles thereof, and in which:

Figure 1 is a diagrammatic side view of a continuous type sheet feeder and part of a press which it serves, illustrating the application of this invention thereto;

Figure 2 is an enlarged side view of the upper portion of the conveyor on the feeder to illustrate the manner in which the independent drive is connected with the feeder;

Figure 3 is an end view of the structure shown in Figure 2;

Figure 4 is an enlarged detail view illustrating the manner in which the independent drive is disconnected from its source of power, said view showing the parts in the positions they should occupy when the independent drive is started;

Figure 5 is a view similar to Figure 4 but show-

ing the parts in the positions they assume as the independent drive is stopped;

Figure 6 is a detail sectional view taken through Figure 5 on the plane of the line 6—6;

Figure 7 is a detail view partly in elevation and partly in section illustrating a slightly modified form of independent drive;

Figure 8 is a side view of part of the feeder to show the manner in which the mechanism for disconnecting this modified independent drive from its source of power is actuated from the feeder; and

Figure 9 is an end view of the upper portion of the mechanism shown in Figure 8 and the switch controlled thereby.

Referring now particularly to the accompanying drawings, in which like numerals indicate like parts, the numeral 5 designates generally a sheet feeder of the continuous type arranged to present sheets singly to a printing press or other machine to be fed, indicated generally by the numeral 6.

As in Reissue Patent No. 20,194, the feeder has its bank supports generally referred to as the upper and lower feed boards mounted at a relatively low elevation to facilitate loading. As a consequence, the sheets, after being separated and fed off the bank in underlapped relation, must be carried upwardly to the elevation of the point of entry of the sheets into the press.

Hence, the conveyor which carries the sheets from the bank or supply to the press has an upright run 7 and a horizontal run 8, the latter overlying the feed board of the press to present the sheets to the front guides 9.

The conveyor is thus quite long; and in view of the fact that the sheets are fed in underlapped relation, it requires a considerable number of cycles of feeder operation to fill the conveyor and advance a sheet from the bank to the front guides.

It is customary to drive the feeder and consequently the conveyor, which really forms part of the feeder, from the press or other machine being fed. This insures synchronism between the feeder and the press.

Ordinarily the drive for the feeder consists of a shaft 10 driven from the press in any suitable manner and drivingly connected through a clutch 11 with the main power input shaft 12 of the feeder. This clutch is of the unidirectional or overrunning type and to insure the feeder and press being in phase, has but a single driving position.

Heretofore, the power take-off just described was the only means for driving the feeder other than the usual hand wheel (not shown) generally secured to the shaft 12. The hand wheel provided means by which the feeder could be turned over manually to enable the same to be adjusted for different sheet sizes and to properly prepare the same for a run.

After adjustment, the operator heretofore either had to turn the feeder over by hand the required number of cycles to fill the conveyor and bring the leading sheet in juxtaposition to the front guides of the press so that upon starting the press a sheet would be in position to be printed; or the press would have to be run without sheets passing through it until the entire conveyor would be filled.

The former procedure obviously is objectionable because of the tedious labor involved; and the latter has the objection of necessitating discarding quite a number of the first sheets

through the press inasmuch as the form would be overinked.

To overcome these objections inherent in all past feeder-press combinations, the present invention provides an independent power drive for the feeder. In that form of the invention illustrated in Figures 1 to 6, inclusive, this independent power drive comprises an electric motor 13 arranged to drive the power input shaft 12 through a belt 14 trained about a pulley 15 connected to one element of a clutch 16 similar to the clutch 11.

Through the clutch 16, the power input shaft 12 may be driven in the proper direction by operation of the motor 13 and entirely independently of the press due to the unidirectional overrunning characteristic of the clutch 11.

Operation of the motor 13 is controlled by a conventional "start-stop," push button switch 17 (see Figures 4, 5 and 6). The "start" button 18 is the upper one and is arranged to be manually depressed in the customary manner to start the motor 13.

The "stop" button 19 is in position to be depressed by a finger 20 carried by a ratchet wheel 21 upon rotation of the ratchet wheel to a switch opening position illustrated in Figure 5. The shaft 22, upon which the ratchet wheel is loosely journaled, is mounted on the inner face of one of the upright frame members 23 which support the upright run 7 of the conveyor.

The ratchet wheel is arranged to be advanced a step at a time during each cycle of operation of the feeder. To this end, a pawl 24 is mounted on the outer end of a lever 25 oscillatable on the shaft 22 by an eccentric 26 driven from a shaft 27 of the feeder which revolves once during each cycle. A detent 28 serves to prevent retrograde rotation of the ratchet wheel.

Hence, it will be apparent that as the feeder operates, the ratchet wheel will be advanced step by step to bring its switch opening arm 20 against the "stop" button 19.

Obviously the number of cycles required to advance a sheet from the bank to the front guides of the press depends upon the length of the conveyor. Hence, the mechanism for automatically opening the switch 17 and stopping the motor 13 must be adjustable.

In this embodiment of the invention, the required adjustment is effected by means of an adjustable stop 29 mounted on the shaft 22 and adapted to be secured thereto in any position of adjustment. A portion of this stop lies in the path of the switch actuating arm 20 to define its start position and thereby determine the number of cycles for which the feeder will be driven by the independent drive.

In the embodiment of the invention illustrated in Figures 7, 8 and 9, the power input shaft 12 is adapted to be driven by an electric motor 30. A clutch 31 of the unidirectional type with one element 32 thereof fixed to the shaft 12 and its other element carried by a gear 33 loose on the shaft 12 (longitudinally and rotatably) provides a separable driving connection between the motor and the shaft 12.

The teeth of the gear 33 are arranged spirally as are also the teeth of a pinion 34 which meshes therewith. The pinion 34 is restrained against axial motion, and the direction of the spiral on the pinion and gear teeth is such that the thrust set up during the driving of the gear by the pinion tends to propel the gear along the

shaft 12 to engage its clutch element with the clutch element 32.

Hence, upon initial operation of the motor 30, the clutch 31 is engaged to drive the shaft 12; and by virtue of the unidirectional characteristic of the clutch, driving of the shaft 12 from the press slides the gear 33 back to disengage the clutch 31.

As in the embodiment of the invention hereinbefore described, the motor of the independent drive is controlled by a switch which may be closed manually but which is automatically opened when the leading sheet on the conveyor arrives at the front guides of the press. This switch designated 35 has its operating lever 36 engaged by a forked lever 37 loosely mounted on a supporting shaft 38 projecting from the adjacent side frame 39 of the conveyor.

Also loosely mounted on the shaft 38 is a ratchet wheel 40 which has a pin 41 projecting therefrom in position to engage the forked lever 37 and swing the same in a switch opening movement. This corresponds substantially to the structure hereinbefore described; and as in the other embodiment, the duration for which the independent drive is operative is set by adjusting a stop 42 which is fixed on the shaft 38, the stop 42 being engageable by the pin 41 and defining the start position of the ratchet wheel.

To positively limit the motion which may be imparted to the arm 37 by the ratchet wheel, a portion 43 of the periphery of the ratchet wheel is left blank so that its pawl 44 merely idles after the switch opening position of the mechanism has been reached.

The pawl 44 is driven by a cam 45 mounted on a clutch controlled cam shaft 46 which makes one revolution for each cycle of operation of the feeder. A cam follower 47 on one end of a medially pivoted lever 48 transmits the cam produced motion to the pawl through a connecting rod 49.

Inasmuch as the shaft 46 is clutch controlled, it may be disconnected from the feeder during the normal operation of the feeder and press to obviate the continual idling motion of the pawl. Any suitable clutch (not shown) may be used to drivingly connect the shaft 46 with the feeder mechanism.

From the foregoing description taken in connection with the accompanying drawings, it will be readily apparent that this invention overcomes one of the objectionable features of present day sheet feeders by providing an independent drive for the feeder which is capable of being set to operate the feeder just long enough to completely fill its conveyor and bring the leading sheet thereon in position to enter the press or other machine being fed.

What we claim as our invention is:

1. In combination: a sheet feeder; a machine to be fed; a conveyor drivingly connected with the feeder for carrying the sheets from the feeder to the machine; a driving connection between the machine and the feeder which when operative compels concomitant operation of the machine and feeder; and independent power driven means for driving the feeder and conveyor independently of the machine so that a sheet may be advanced while the machine is idle to a position at which the sheet instantly enters the machine upon starting the machine.

2. The combination with a printing press and a sheet feeder therefor including a conveyor for carrying sheets from the feeder to the press, and

means for driving the feeder and conveyor from the press: of power driven means for driving the feeder and conveyor independently of the press to enable advancing a sheet to the front guides of the press without necessitating operation of the press.

3. The combination with a printing press and a sheet feeder therefor including a conveyor for carrying sheets from the feeder to the press, and means for driving the feeder and conveyor from the press: of power driven means for driving the feeder and conveyor independently of the press to enable advancing a sheet to the front guides of the press without necessitating operation of the press; and means for automatically stopping said power driven independent drive when the sheet reaches the front guides of the press.

4. In a sheet feeder for printing presses and the like having means for driving the feeder from the press and wherein a conveyor carries the sheets to the entry point of the press where its front guides are located: independent power driven means for operating the feeder and conveyor independently of the press so that the feeder may be run while the press is idle to completely fill the conveyor and bring the leading sheet on the conveyor to the front guides of the press; and means for automatically stopping said independent power driven means to stop the feeder and conveyor the instant the leading sheet arrives at the front guides of the press.

5. In a sheet feeder having a conveyor for carrying sheets singly to a machine to be fed, said conveyor advancing the sheets it carries a predetermined distance for each cycle of operation of the feeder so that the transfer of a given sheet from the source of supply to the end of the conveyor requires a number of cycles of operation of the feeder, depending upon the length of the conveyor: power driven means for driving the feeder; means for automatically stopping said power driven means, said means being movable toward a stopping position a step at a time for each cycle of operation of the feeder; and means for setting the stopping means so that said stopping means becomes operative to stop the feeder after any desired number of cycles of operation of the feeder.

6. In a sheet feeder for feeding sheets to a printing press or the like in a continuous stream with the successive sheets underlapped: a conveyor for carrying the underlapped stream of sheets to the press; means for driving the feeder from the press; an independent drive for the feeder by which the feeder and conveyor may be run independently of the press so that the conveyor may be completely filled and the leading sheet brought to the front guides of the press while the press is idle, said conveyor advancing the stream of underlapped sheets a step at a time for each cycle of operation of the feeder so that the arrival of the front edge of the leading sheet at the front guides of the press requires a predetermined number of cycles of operation of the feeder, depending upon the length of the conveyor; and adjustable means for automatically stopping said power drive after the feeder has run the required number of cycles to bring the leading sheet to the press, the adjustability of said automatic stopping means enabling the stopping of the feeder the instant the front edge of the leading sheet arrives at the front guides of the press regardless of the length of the conveyor.

7. In a sheet feeder having a conveyor for

carrying sheets to a machine to be fed: a drive for operating the feeder and the conveyor entirely independently of the machine with which the feeder is associated, said drive being powered by an electric motor; a switch controlling connection of the motor with its source of current; and means automatically operable to open the switch at a predetermined time coordinated with the advance of sheets by the conveyor so that the feeder stops when the leading sheet on the conveyor reaches a predetermined position with relation to the machine being fed.

8. In a sheet feeder having a conveyor for carrying sheets to a machine to be fed: a drive for the feeder entirely independent of the machine with which the feeder is associated, said drive being powered by an electric motor; a switch controlling connection of the motor with its source of current; means automatically operable to open the switch at a predetermined time coordinated with the advance of sheets by the conveyor so that the feeder stops when the leading sheet on the conveyor reaches a predetermined position with relation to the machine being fed; and means for adjusting the switch opening means so that the time of opening of the switch may be set in accordance with the length of the conveyor.

9. In a sheet feeder having a conveyor for carrying sheets to a machine to be fed: a power drive for the feeder independent of the machine with which it is associated and by which the feeder may be run independently of the machine being fed to fill its conveyor with sheets and to bring the leading sheet in position to enter the machine being fed, said feeder operating cyclically and advancing the sheets on the conveyor a predetermined distance for each cycle so that the arrival of the leading sheet at the machine being fed requires a predetermined number of cycles of operation, depending upon the length of the conveyor; and means for automatically stopping said power drive, said means being advanced a step at a time toward stopping position by the cyclical operation of the feeder.

10. In a sheet feeder having a conveyor for carrying sheets to a machine to be fed: a power drive for the feeder independent of the machine with which it is associated and by which the feeder may be run independently of the machine being fed to fill its conveyor with sheets and to bring the leading sheet in position to enter the machine being fed, said feeder operating cyclically and advancing the sheets on the conveyor a predetermined distance for each cycle so that the arrival of the leading sheet at the machine being fed requires a predetermined number of cycles of operation, depending upon the length of the conveyor; means for automatically stopping said power drive, said means being advanced a step at a time toward stopping position by the cyclical operation of the feeder; and means adjustable to effect stopping of the power drive after any desired number of cycles of operation so that the stopping of the feeder may be set to occur at exactly the instant the leading sheet arrives at the machine being fed.

11. In a sheet feeder having a conveyor for carrying sheets to a machine to be fed: a power drive for the feeder independent of the machine with which it is associated and by which the feeder may be run independently of the machine being fed to fill its conveyor with sheets and to bring the leading sheet in position to enter the machine being fed, said feeder operating cyclical-

ly and advancing the sheets on the conveyor a predetermined distance for each cycle so that the arrival of the leading sheet at the machine being fed requires a predetermined number of cycles of operation, depending upon the length of the conveyor; a member movable to stop said power drive; and means advanced by the feeder step by step toward said member and operable to move the same and stop the feeder after a predetermined number of cycles of operation.

12. In a sheet feeder having a conveyor for carrying sheets to a machine to be fed: a power drive for the feeder independent of the machine with which it is associated and by which the feeder may be run independently of the machine being fed to fill its conveyor with sheets and to bring the leading sheet in position to enter the machine being fed, said feeder operating cyclically and advancing the sheets on the conveyor a predetermined distance for each cycle so that the arrival of the leading sheet at the machine being fed requires a predetermined number of cycles of operation, depending upon the length of the conveyor; a member movable to stop said power drive; means advanced by the feeder step by step toward said member and operable to move the same and stop the feeder after a predetermined number of cycles of operation; and means for adjusting the relationship between said movable member and said cyclically advanced actuating means to effect feeder stopping motion of said member at different times.

13. In a sheet feeder for feeding sheets to a press or other machine having a conveyor to carry the sheets to the press and having a main power input shaft: a driving connection from the press to said power input shaft; an independent power drive for the feeder and conveyor for driving the feeder entirely independently of the press or other machine; a driving connection between said power drive and said main power input shaft; and clutches in said driving connections so that either of said driving connections may be operative to drive the feeder without effecting the other driving connection.

14. In a sheet feeder: a conveyor; means for driving the conveyor including an electric motor; a switch controlling operation of the motor; means for stopping the motor including a member movable to open the switch; means driven from the motor for actuating the switch opening member toward its operative switch opening position; and manually adjustable connecting means between the switch opening member and its driving means so that the time of switch opening may be set to occur after a predetermined period of feeder operation.

15. In a combination sheet feeder and printing press or other machine fed by the feeder wherein sheets are carried singly from a source of supply to the press or other machine being fed: means for driving the feeder and conveyor from the press or other machine being fed; a separate power drive for the feeder and conveyor entirely independent of the press or other machine; a clutch incorporated in said separate drive; means for automatically engaging said clutch during initial operation of said separate drive; and means for automatically disengaging said clutch upon the application of driving force from the press or other machine to the feeder.

16. In a sheet feeder having a power input shaft: a drive for the feeder including a prime mover; a gear; a clutch for connecting the gear with said power input shaft, said clutch being

engageable and disengageable by endwise motion of the gear; and a pinion driven by the prime mover and meshing with said gear, the teeth of the pinion and gear being arranged spirally to impart an end thrust to the gear in a direction to engage the clutch upon starting of the prime mover.

17. In a sheet feeder having a power input shaft: a drive for the feeder including a prime mover; a gear; a clutch for connecting the gear with said power input shaft, said clutch being engageable and disengageable by endwise motion of the gear; a pinion driven by the prime mover and meshing with said gear, the teeth of the pinion and gear being arranged spirally to impart 15 an end thrust to the gear in a direction to engage

the clutch upon starting of the prime mover; and means responsive to the application of driving force on said power input shaft while the prime mover is idle for automatically disengaging the clutch.

18. In combination: a sheet feeder having a conveyor drivingly connected therewith to deliver sheets to the machine from the feeder; a machine to be fed; a driving connection between the machine and the feeder which when operative compels concomitant operation of the machine and feeder; and independent power driven means for driving the feeder and the conveyor independently of the machine.
